(57) **CLAIM**

The ornamental design for a compost spreading and top dressing apparatus, as shown and described.

DESCRIPTION

FIG. 1 is a left side elevational view of the compost spreading and top dressing apparatus showing my new design, the apparatus being oriented in a position at which the apparatus is normally connected to a prime mover (not shown);

FIG. 2 is a front elevational view of the compost spreading and top dressing apparatus shown in FIG. 1;

FIG. 3 is a right side elevational view of the compost spreading and top dressing apparatus shown in FIG. 1;

FIG. 4 is a rear elevational view of the compost spreading and top dressing apparatus shown in FIGS. 1-3;

FIG. 5 is an upper, front perspective view of the compost spreading and top dressing apparatus showing the top and the internal features of the apparatus; and,

FIG. 6 is a left, rear perspective view of the compost spreading and top dressing apparatus depicted in FIGS. 1-5. FIGS. 2, 4 and 5 are shown on an enlarged scale.

The broken lines are for illustrative purposes only and form no part of the claimed design.
